[57] CLAIM

The ornamental design for a replaceable gas analyzer, as shown and described.

DESCRIPTION

FIG. 1 is a perspective view from the top, rear, left side thereof;

FIG. 2 is a perspective view from the top, front, right side thereof;

FIG. 3 is an elevational view from the left side thereof, the right elevational view being a mirror image of the view illustrated in FIG. 3;

FIG. 4 is a plan view from the top side thereof;

FIG. 5 is a plan view from the bottom side thereof;

FIG. 6 is an elevational view from the front thereof;

FIG. 7 is an elevational view from the rear thereof;

FIG. 8 is an exploded perspective view from the top, rear, left side thereof, illustrating the relationship between the replaceable gas analyzer and a stationary manifold, it being understood that the broken line showing of environment is for illustrative purposes only and forms no part of the claimed design;

FIG. 9 is an elevational view from the left side thereof, illustrating a replaceable gas analyzer with a stationary manifold; and,

FIG. 10 is the same view as FIG. 9 with the replaceable gas analyzer separated from the stationary manifold.
